BUMP DETECTOR

Clyde P. Grant, Gorham, Gilbert Forrester, Falmouth, and Robert L. Smith, Gorham, Maine, assignors to S. D. Warren Company, Boston, Mass., a corporation of Massachusetts

Filed May 13, 1959, Ser. No. 812,895
6 Claims. (Cl. 73—159)

This invention relates to improved means for detecting abrupt changes in caliper of a moving web of flexible material such as paper.

In the manufacture of fine paper, it has been found feasible to inspect a paper web for defects just before it is cut into sheets and to provide means for automatically sorting and separating sheets that have defects from sheets that are free of defects. Various types of devices are used for inspecting the web for predetermined types of defects and for generating an electrical signal which will operate the sorting mechanism at the proper time to eliminate a defective sheet.

Detecting bumps or abrupt changes in caliper of a web has been especially bothersome. While devices have been made which will detect substantially all bumps or abrupt changes in caliper of a certain magnitude, they have been subject to certain limitations, as, for example, accuracy only at low web speeds or false indications of a bump due to certain physical or chemical characteristics of the web, as, for example, moisture.

The object of this invention is to provide a new type of bump detector which is free of the limitations attendant to bump detectors heretofore devised.

A more specific object of this invention is to provide means for detecting sharp changes in the caliper of a moving web and for generating an electrical signal each time an abrupt change is discovered.

Another specific object of this invention is to provide a bump detector capable of operating efficiently regardless of the physical and chemical characteristics of the web being inspected.

Other objects and many of the attendant advantages of the present invention will be more readily appreciated as the invention becomes better understood by reference to the following detailed description when considered in connection with the accompanying drawings, wherein:

FIG. 1 is a perspective view showing a plurality of bump detector skids positioned in operating relation to a paper web;

FIG. 2 is an enlarged plan view of one of the skid members;

FIG. 3 is a sectional view in elevation of the assembly of FIG. 1;

FIG. 4 is a sectional view taken along line 4—4 of FIG. 3;

FIGS. 5 and 6 are enlarged fragmentary side views of two modified forms of skid; and

FIG. 7 is a schematic diagram of an electric system employed with the skids to generate an electrical signal when a bump is detected.

Referring now to FIG. 1, there is shown a portion of a bump detector assembly for use in a machine for (1) inspecting a paper web for predetermined types of defects, (2) cutting said web into sheets, and (3) separating defective sheets from sheets that are free of defects. Such a machine is disclosed in our copending application for Apparatus for Inspecting, Cutting, and Sorting Paper, Serial No. 776,342, filed November 25, 1958.

The bump detector assembly comprises a horizontal beam 2 mounted above and slightly upstream of a roll 4 which supports a moving paper web 6. Roll 4 may be a driven roll, or, if the paper is driven by other rolls, it may be simply an idler roll. Attached to the beam 2

2

by means of bolts 8 is a series of brackets 10 each having a pair of parallel-spaced horizontal arms 12 which project in a downstream direction away from beam 2. Brackets 10 extend in an even line along beam 2 and function to support a plurality of skids identified generally by numeral 14.

Referring now to FIGS. 1, 2, and 3, each skid 14 comprises a body portion made up of two relatively thick plates 16 and 18 held in superposed relation by screws 20 and a rectangular metallic plate 22. A substantial portion of plate 22 is sandwiched tightly between plates 16 and 18. The latter are provided with matching semi-cylindrical grooves which define a channel in which is held a tube 24 whose ends contain bearings 26 and 28. Rotatably journaled in these bearings and extending beyond the ends of tube 24 is a shaft 30. The ends of shaft 30 are supported by the two arms 12 of bracket 10. Arms 12 are provided with V-shaped notches 32 which function as seats for the ends of shaft 30. The latter are releasably held down in notches 32 by latches 34 which are pivotally secured to arms 12 by means of screw bolts 36 which are screwed into tapped openings 38 in arms 12. Bolts 36 are made tight so as to prevent latches 34 from turning as a result of any vibration of the apparatus during operation. Tube 24 is located so that the center of gravity of the skid is slightly forward of shaft 30.

Although each plate 22 may be perfectly flat at its forward edge, it is preferred that each one be bent to form a lip 40 at that edge. Lip 40 makes the edge more rigid and reduces any tendency for the plate to flex cornerwise or about the line of symmetry of the skid. The line of symmetry of the skid is indicated by the broken line C—C in FIG. 2. Accordingly, any force applied to a portion 35 of plate 22 will cause it to bend or flex along a line running parallel to its forward edge. Since plate 22 is anchored only along one edge, it is similar to a cantilever beam; and, accordingly, any flexing which it experiences tends to occur along the line of the forward 40 edges 42 of plates 16 and 18.

Assuming now that web 6 has a bump in its top surface and that it is traveling at an appreciable speed, as, for example, 200 feet per minute, the bump will produce a sharp blow on one of the skids as it travels over roll 4. Because the center of gravity of the skid is downstream 45 of shaft 30, the skid will have a moment of inertia that tends to prevent the skid from pivoting upward. Consequently, the metal plate 22 will yield first to absorb the effect of the blow and to allow the bump to pass 50 on downstream, and almost instantaneously thereafter, the skid will pivot upward in reaction to the energy absorbed by the plate. In yielding to the bump, the metal plate bends upward (i.e., flexing) relative to the body portion of the skid. This flexing action is sufficiently 55 small in magnitude and occurs so fast as not to be discernible to the naked eye. However, it is of sufficient magnitude to be detected.

In the illustrated embodiment of the invention, the deflection of the metal plates in response to bumps or rapid 60 changes in web caliper is detected by means of a crystal-type phonograph pickup head identified generally by numeral 46. The head is provided with a pair of flanges 48 and 50 which are provided with holes to receive screws 52 which cooperate with nuts 54 to anchor the head to 65 a bracket 56. Preferably, but not necessarily, flanges 48 and 50 are sandwiched between resilient washers 58 made of rubber or other suitable material. Bracket 56 is made of rigid metal and has upturned sides 60 and 62 which prevent it from flexing about its center. The bracket is fastened by short screws 64 and 66 to the top 70 half 16 of the body portion of the skid and is oriented so that the forward end of the pickup head overlies metal

plate 22. Pickup 46 is disposed slightly to one side of the center line C—C of the skid. Secured to the cartridge in the hole normally occupied by a phonograph needle is a wire rod element 68 comprising a first inclined portion 70 formed integral with a second horizontally extending portion 72. The top end of portion 70 is secured within the pickup head by a set screw 74. To the free end of portion 72 is secured a conventional hex nut 76. Mounted in nut 76 is a screw 78. Screw 78 is turned down into snug, but not tight, contact with plate 22 at a point approximately half-way between its side edges and preferably, but not necessarily, it contacts the plate at a point offset from the line of contact of the plate with roll 4, as in FIG. 3. This assures optimum and substantially uniform response for all deflections caused by bumps anywhere along the entire width of the skid.

The pickup head has two output terminals 80 and 82 which are connected by means of a two-wire cable 86 to the output circuit illustrated in FIG. 7.

Referring now to FIG. 7, the two terminals of pickup head 46 are connected to a band pass filter. More particularly, they are connected in series with two capacitors 92 and 94, two resistors 96 and 98, a third capacitor 100, and a third resistor 102 which is part of a potentiometer 104. Terminal 82 is grounded. A resistor 106 is connected at one end to the juncture of capacitors 92 and 94 and at the other end to ground. Another resistor 108 is connected between capacitor 94 and resistor 96 and at the other end to ground. A capacitor 110 is connected on one side to the juncture of resistors 96 and 98 and at the other side to ground. Still another capacitor 112 is connected on one side to ground and on the other side to the juncture of resistor 98 and capacitor 100. Capacitors 92 and 94 and resistors 106 and 108 have values suitable to pass all signals above approximately 200 cycles. The remaining resistors and capacitors have values suitable to pass all signals below 2000 cycles. As a result, spurious 60-cycle and other low-frequency signals resulting from machine vibration or motor hum and any stray high frequency signals are eliminated, and only signals between 200 and 2000 cycles are passed. It has been found that signals generated by bumps in a paper web are concentrated in that band and that elimination of all other signals provides a great increase in response.

Potentiometer 104 has a slider 116 which is coupled directly to the control grid 118 of the left-hand half of a twin triode 120. Both cathodes 122 are connected to ground. The right- and left-hand plates 124 and 126 are connected in parallel with a positive voltage supply 128 through load resistors 130 and 132 respectively. Plate 124 is connected to the right-hand grid 134 by a capacitor 136. A resistor 138 is connected on one side to ground and on the other side to the juncture of grid 134 and capacitor 136. Capacitor 136 and resistor 138 function as a differentiating circuit. Plate 126 is connected by a capacitor 140 to the control grid 142 of the pentode section of a combination pentode-triode tube 144. A resistor 146 is connected between ground and the junctures of capacitor 140 and control grid 142. Capacitor 140 and resistor 146 function as a differentiating circuit. The plate 148 of the pentode is connected by a load resistor 150 to voltage supply 128. The screen grid 152 is connected by load resistor 154 to the same voltage supply. The suppressor grid 156 and pentode cathode 158 are connected to ground through a resistor 160. Suppressor grid 156 is connected also to voltage supply 128 through a resistor 162.

The control grid 164 of the triode section of tube 144 is connected by a capacitor 166 to plate 148 of the pentode. A capacitor 168 is connected between ground and the juncture of grid 164 and capacitor 166. A resistor 170 is connected in parallel with capacitor 168.

The triode plate 172 is connected to a second positive voltage supply 174 through the coil 176 of a switching

relay 178. The latter has two normally closed switch contacts 180 and 182 which are opened when coil 176 is energized. Contact 180 is connected to an oscillator 184, and terminal 182 is connected to a magnetic recorder 186.

Operation of the system of FIG. 7 will now be described. When a bump in the moving paper web strikes a skid, it causes flexing of its metal plate 22. This in turn causes movement of screw 78 which in turn causes distortion of the crystal in the pickup head. This distortion is translated into an electrical signal having a generally sine wave shape. This signal is filtered and applied to grid 118 for amplification by the left-hand section of tube 120. Slider 116 is adjusted for proper gain. The amplifier signal is fed to grid 134 for further re-amplification in the right-hand section of tube 120. The amplified signal appearing at plate 126 is differentiated by capacitor 140 and resistor 146, and the resulting pulses are applied to control grid 142 of the pentode section of tube 144. This pentode section is always conducting but below the linear portion of its operating wave. Hence, it amplifies positive pulses to a greater extent than negative pulses. These positive and negative pulses are amplified and inverted and applied to the control grid 164. The right-hand half of tube 144 is normally conducting but is driven to cutoff by the negative pulses applied to grid 164. When the right-hand half of tube 144 is driven to cutoff, coil 176 is deenergized, and contacts 180 and 182 reclose to couple oscillator 184 to recorder 186. The right-hand section of tube 144 remains cut off for a short while after the negative pulse applied to its grid 164 has passed. This is necessary in order to allow the coil 176 to be deenergized long enough for contacts 180 and 182 to close. The right-hand half of tube 144 is kept off by the voltage appearing across capacitor 168. The time duration of the cutoff period of the tube is determined by the charge across capacitor 168 and the RC time constant of capacitor 168 and resistor 170. The negative voltage across capacitor 168 bleeds off through resistor 170, and the right-hand half of the tube begins to conduct again when the voltage across capacitor 168 returns above the cutoff voltage.

It has been found that the signal generated by a bump is of relatively short duration and decays rapidly to zero. Thus, the generated signal train is so short as to appear as a single negative pulse at grid 164. It is believed to be obvious that any positive pulses which appear at grid 164 are so small as not to interfere with operation of the circuit as just described.

It is to be noted that while the system shown in FIG. 7 includes a recorder for preserving the short output of oscillator 184, such a recorder is not necessary and is illustrated simply to show how the present invention may be substituted for the bump detector system of the apparatus disclosed in our copending application Serial No. 776,342. The output of the oscillator passed by relay 178 need not be applied to a recorder but may, for example, be applied to an alarm system. Similarly, the oscillator may be omitted and relay 178 may be employed to operate some other device, as, for example, a warning light.

It is to be understood that the pickup heads for several skids may be connected in parallel to a single electrical system like the one shown in FIG. 7, or each pickup head may have its own system. It is further contemplated that the phonograph pickup heads need not be of the crystal type but may be of the magnetic type as well.

The invention is not limited to the exact skid shown in FIGS. 1 and 2. In fact, it is preferred to attach to the underside of metal plate 22 a separate riding shoe 190 (FIG. 5) which can be readily replaced when worn. Shoe 190 is attached by means of a plurality of screws 192. Alternatively, the shoe may be attached by a suitable adhesive or may be shaped or molded so that it may be attached without screws, as by gripping the plate edge.

in a tight groove. Preferably, the edges of the shoe are beveled as shown at 194 so as to provide better contact with the paper web. The shoe may be made out of any suitable material, preferably a plastic. Teflon has been found to be especially suitable.

It is to be understood also that the metal plate 22 need not have the sharp right-angle lip 40. Instead, if the metal plate is sufficiently rigid, the lip may be omitted entirely. Alternatively, the lip may be formed by a more gentle curve, like the lip 40a shown in FIG. 6.

Obviously, many modifications and variations of the present invention are possible in the light of the above teachings. It is to be understood, therefore, that the invention is not limited in its application to the details of construction and arrangement of parts specifically described or illustrated, and that within the scope of the appended claims, it may be practiced otherwise than as specifically described or illustrated.

We claim:

1. Apparatus for detecting abrupt changes in caliper of a moving web of paper comprising a roll for supporting said web, a skid support disposed adjacent to said roll, a skid having a body portion pivotally secured to said support with a flexible extension urged into light contact with said moving web, a transducer mounted on said body portion, and a probe on said transducer coupled to said flexible extension and responsive to relative motion between said extension and said body portion for translating flexing of said skid caused by an abrupt change in caliper of said web into an electrical signal indicative of said abrupt change in caliper.

2. Apparatus for detecting sharp changes in caliper of a moving web of paper comprising a horizontal roll for supporting said moving web, a skid supporting member located above and extending parallel to said roll, a skid comprising a relatively thick flat substantially inflexible body member pivotally secured to said skid supporting member and a relatively thin flexible but torsion-resistant member for engaging said moving web along a transverse line, an elongated pickup probe in contact with said torsion-resistant member and movable in response to flexing

of said same member relative to said body member, a transducer element mounted on said body member and supporting said pickup probe for producing an electrical signal in response to movement of said probe, and means for amplifying said signal.

5 3. Apparatus as defined by claim 2 wherein said transducer is a crystal-type phonograph pickup cartridge.

4. Apparatus as defined by claim 2 wherein said transducer is a magnetic-type phonograph pickup cartridge.

10 5. Apparatus as defined by claim 2 further including means connecting said transducer and said amplifying means for eliminating signals having (1) a frequency below 200 cycles and (2) signals having a frequency above 2000 cycles.

15 6. Apparatus for detecting sharp changes in caliper of a moving web as it moves over a roll, comprising a fixed member located above and extending transversely of the moving web, a skid pivotally attached to said fixed member, said skid comprising first and second flat relatively thick rigid members and a third flat flexible relatively thin member having a first portion thereof sandwiched tightly between said first and second members, said third member having a second portion in engagement with said moving web, a phonograph pickup head attached to one 20 of said first and second members, said pickup head having a pickup element in engagement with the said second portion of said third member, and signal generating means connected to said pickup head for producing an output signal each time said pickup element is moved by flexing 25 30 of said third member.
